WRITING INSTRUMENT

Hans R. Fehling, London, England, assignor, by
mesne assignments, to Eversharp, Inc., Chicago,
Ill., a corporation of Delaware

Application December 26, 1946, Serial No. 718,336
In Great Britain June 7, 1946

3 Claims. (Cl. 120—42.4)

1

This invention relates to writing instruments and, more particularly, to the type in which a rotatable ball writing member is mounted for rotation in a housing with part of the ball exposed.

In the type of instruments herein indicated, the unexposed part of the ball is housed and in contact with a supply of ink contained in the instrument. As the writing ball member of the instrument is rotated by being moved over and in contact with a writing surface, a thin film of ink is carried by the ball through the gap between the ball and the housing and this is deposited as a trace on the writing surface. The ink used is preferably a viscous ink of the type disclosed in pending applications Serial Numbers 389,829, now Patent 2,416,145; 657,598, now abandoned; and 659,149, now abandoned, filed April 23, 1941, March 27, 1946, and April 2, 1946, respectively.

The housing for the rotatable ball member forms part of the terminal or nib portion of the instrument and is in communication with a source of ink in such writing instrument. It is important that the ball member be well supplied with ink from the instrument without forming any smudges when the instrument is in use and that the size of the gap between the ball and the housing be between 1×10^{-4} and 1×10^{-3} cms. (1 to 10 microns).

With the above and other features in view, it is an object of the invention to effect improvements in a writing extremity or "nib" for writing instruments of the type such as are shown and described in co-pending application S. N. 674,262, filed June 4, 1946, now Patent 2,536,924.

As explained in the said patent applications, the size of the gap between the ball and the housing is a critical factor in the efficient operation of the writing instrument. It will, however, be noted that there is a progressive tendency for the gap to widen under prolonged use owing to wear and this widening eventually results in the pen smudging instead of leaving a sharply defined and distinct trace.

Another object of the present invention is to provide an instrument with a fissured ball housing provided with means for feeding ink to the ball member and adapted to compensate for the wear on the housing.

A further object of the present invention is to provide a writing instrument with a terminal or nib portion having a housing containing a rotatable ball member and forming a gap whose size remains practically constant irrespective of wear.

2

With the above and other objects in view, the invention will now be described in detail with reference to the accompanying drawings in which

Fig. 1 is an elevational view of an embodiment of the invention;

Fig. 2 is a longitudinal, sectional, fragmentary, enlarged view of the terminal or nib portion of an instrument shown in Fig. 1;

Fig. 3 is a cross sectional view taken on line 10 3—3 of Fig. 2;

Fig. 4 is a longitudinal, sectional, fragmentary view of a modified form of the embodiment shown in Fig. 1; and

Fig. 5 is a longitudinal, sectional, fragmentary 15 view of another form of the invention.

In the drawings showing exaggerated views, like reference characters refer to like parts throughout.

In Fig. 1 is illustrated a writing instrument 7 20 of the ball point type having a tubular housing 8 and a tapering end portion 9 in the forward end of which is mounted a rotatable writing ball member 10. Said housing contains an ink reservoir such as is described in the co-pending applications previously referred to herein and is adapted to supply ink to the ball member 10.

Referring to Figs. 2 and 3, which show the details of construction of the end portion 9, a ball 10 is shown as contained in a housing 12, with its upper portion or lip 14 having spaced diametral slits 16 of a capillary size, e. g., of about 0.1 mm. in width, which sub-divide said lip of the housing into separate fingers 18 each serving to enclose the ball 10 as in the jaws of a chuck.

It will be noted that said fingers are springy, equi-spaced and substantially vertically disposed, as shown, and may extend to the diametric plane of the ball member 10. The gap 20 formed between the housing and the ball member is slightly exaggerated, being shown much wider than it actually is. Said fingers 18 have a certain degree of resiliency and, as wear on their interior faces takes place, such as would normally tend to increase the size of the ink filled gap 20, they

themselves tend to close and to maintain the gap size substantially constant; e. g., at a preferred value of about 5 microns.

It may here be understood that, although the vertical slits 16, formed in the lip 14, permit ink to flow therethrough, it will be appreciated that, since these slits are of a capillary size, they constitute narrow capillary channels and serve to hold the ink in them in very much the same manner as the narrow gap or slit between the two tongues or points of the ordinary type of

pen nib which serves to hold and conduct the extremely fluid ink employed in said type of pens. In effect, it will be noted that the slits provide alternative or supplementary means for conveying ink around the ball rather than facilities for draining the lateral seating and gap by seepage through them to the outside of the nib housing.

This effect is strongly enhanced by making the slits extremely narrow. The desired fine proportions can be achieved by closing-up, for example, by swaging or pressing, the cuts first made by a saw blade of a practical width, in the order of about 0.5 mm. In this manner slits may be produced having a width of no more than 0.01 mm, or 10 microns. This closing in no way detracts from and indeed may enhance the resilient character or chuck action of the fingers 18.

The depths of the slits 16 in the axial or longitudinal direction of the nib may be varied. Since Figs. 2 and 3 illustrate the slits as cut down to the diametral plane of the ball 10, the fingers 18 are constituted solely by the peined-over part of the lateral seating of the lip 14, it being understood that the ball is retained in its seating by peining the lip thereof. Furthermore, the ball seat 24 is provided in its base 26 with a plurality of grooves 22 extending outwardly of conduit 28. By the presence of grooves 22 between writing member 10 and the front end of ink passage 28, the writing member is directly exposed to the ink from said passage over an area of the writing member substantially larger than the size of said passage.

In Fig. 4, it will be noted that vertical slits 16 may be cut down to substantially the full depth of the ball 10 in housing 12 thereby imparting a greater length to the fingers 18. The use of slits, as shown in this figure, produces a greater resilience and power of adjustment in the fingers 18 and also renders unnecessary the grooves 22 in ball seat 24 and which, as shown in Fig. 2, are formed in the base 26 of the seating 24 so as to lead outwards from the conduit supply passage 28 from an ink reservoir, not shown, but usually of the type shown in co-pending applications hereinabove referred to.

In Fig. 5 are shown slits 16 extending beyond the depth of ball 10 and which may be made in any usual manner, such as with a circular saw. The constructions shown in Figs. 4 and 5 have the further advantage that the ball seating area may be larger than any known constructions because the base of the seating may be produced by the application of a punch having a hemispherical end and because the necessity for grooves 22, as shown in Fig. 1, is obviated.

From the foregoing description taken in connection with the drawings, it will be noted that there are two approaches to a solution of the problem of supplying ink to the writing member without causing smudging after the housing wears down. One is the choice of better materials with better surface finishes thereon, and the second and preferred choice is the compensation for wear by providing means for maintaining the gap substantially constant as wear takes place. It is with this second approach that the present invention is concerned. Compensation for wear of the housing due to use of the ball member therein, however, involves major problems that are mainly due to the small size of the terminal portion of the instrument, known as the nib. Also, the components of said terminal portion of the instrument impose severe manufacturing limitations that will readily be appreciated from

the fact that it is desirable to employ a ball of about 1 mm. in diameter.

Furthermore, the writing extremity or "nib" of an instrument of the type specified, is characterized in that the extreme end or lip portion of the ball housing is split by at least one narrow slit of a capillary size so as to grip the ball resiliently. Within limits, therefore, the resilience thus afforded causes the gap size to remain substantially constant irrespective of wear. It is preferred to provide a plurality of slits at various intervals in the periphery of the lip so that the housing is sub-divided into a plurality of independent resilient and elastic elements which may be referred to as fingers and which, owing to their elasticity, cooperatively grip the ball as in a chuck.

It will be readily observed that, in the production of a terminal writing portion or nib for writing instruments of the rotatable ball point type, the blank nibs are first machined, then one or more vertically disposed slits are formed in the lip section of said nib which are partially closed by means of swaging. The nibs are then drilled in order to form the conduit 28, said conduit being of about 0.5 mm. in diameter. The seating or base 26 is formed in any suitable manner by punching or counterboring and then formed into a hemispherical shape by means of a hemispherical punch.

After this sequence is completed, the known operations of inserting the ball into the seating, peining over the lip of the housing, pressing the ball out, and re-inserting it under pressure, are followed. The material of which the nib is made is preferably a high tensile material having a sufficiently high elastic limit in order to provide the chuck action without permanent distortion.

While various forms have been described in connection with the accompanying drawings, it will be noted that various changes as to form, use, cooperation and arrangement of materials may be made without departing from the spirit and scope of the accompanying claims.

I claim:

1. A writing instrument comprising a casing, a terminal portion extending from the casing, and a spherical writing member rotatably housed in the terminal portion adapted to be coated with ink fed from an ink reservoir in the casing, said terminal portion having a lip constituted by a plurality of springy sections which rotatably retain the writing member and are separated from one another by means of fissures, which fissures are of such minute width as to retain ink therein and prevent the escape of any appreciable quantity of ink laterally therethrough.

2. A writing instrument comprising a casing, a terminal portion extending from the casing, and a spherical writing member rotatably housed in the terminal portion adapted to be coated with ink fed from an ink reservoir in the casing, said terminal portion having a lip constituted by a plurality of springy sections which rotatably retain the writing member and are separated from one another by means of fissures, which fissures are of such minute width as to retain ink therein and prevent the escape of any appreciable quantity of ink laterally therethrough, and said terminal portion including an ink feed passage behind the writing member through which ink is adapted to be fed to the writing member from the reservoir, and said fissures extending about the writing member into communication with said ink feed passage.

3. A writing instrument comprising a casing, a terminal portion extending from the casing, and a spherical writing member rotatably housed in the terminal portion adapted to be coated with ink fed from an ink reservoir in the casing, said terminal portion having a lip constituted by a plurality of springy sections which rotatably retain the writing member and are separated from one another by means of fissures, which fissures are of such minute width as to retain ink therein and prevent the escape of any appreciable quantity of ink laterally therethrough, and said terminal portion including an ink feed passage behind the writing member through which ink is adapted to be fed to the writing member from the reservoir, said terminal portion also including a socket for the writing member which is of spherical shape opposite the sides of the latter and conforms closely to said sides and which is of non-spherical shape behind the writing member at a point between the latter and the front

5

end of said ink feed passage, whereby the writing member is directly exposed to the ink from said passage over an area of the writing member substantially larger than the size of said passage.
